UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

SIDE BEARING FOR RAILWAY CARS.

Application filed January 5, 1923. Serial No. 610,757.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway Cars, of which the following is a full, clear, concise, and exact description, reference being had to the accompanying drawings, forming a part of this specification.

This invention relates to improvements in side bearings for railway cars.

One object of the invention is to provide a simple and efficient gravity centering side bearing and one especially adapted for attachment to the body bolster of a car.

Another and more specific object of the invention is to provide a side bearing of the type specified composed of three pieces, nested together, and held in assembled relation when attached to the car.

In the drawings forming a part of this specification Fig. 1 is a transverse sectional view through the body and truck bolsters of a railway car showing in side elevation my improved side bearing. Fig. 2 is a vertical sectional view through the body and truck bolster showing my improved side bearing in end elevation. And Fig. 3 is a vertical sectional view taken substantially on the line 3—3 of Fig. 1 showing certain parts in elevation.

In said drawing, 10 indicates the lower portion of a body bolster and 11 the upper portion of a truck bolster of a railway car, my improved side bearing being shown as attached to the body bolster.

The improved side bearing comprises, broadly, a supporting member A, a swinging retaining member B and an antifriction roller bearing C.

The supporting member A, comprises a downwardly projecting head 12 and upper laterally extending arms 13 and 14. The supporting member A is secured to the body bolster 10 by rivets 15, or any other suitable means. In the upper face of the supporting member A is formed a depression 16 to provide a curved bearing surface 17, and the downwardly projecting head 12 of the supporting member is provided with a convex lower bearing surface 18 adapted to contact with the anti-friction roller C.

The retaining member B comprises a pair of substantially T-shaped plates 19 con-

nected by a cylindrical journal member 20 integral therewith. The journal member 20 extends through the depressed portion 16 of the supporting member and is adapted to turn on the bearing surface 17 when the body and truck bolsters are separated a sufficient distance to lift the roller C out of contact with the truck bolster. Each of the plates 19 is provided with a downwardly extending relatively broad arm 21, and laterally projecting side arms 22 at its upper end. As clearly shown in Fig. 1, the upper ends of the plates 19 are cut away to provide downwardly and outwardly inclined faces 23 extending from the center of said retaining member to the outer ends of the arms 22. In this connection it will be noted that the upper ends of the plates 19 and the upper side of the cylindrical journal member 20 are normally slightly spaced from the lower face of the body bolster 10 to prevent actual contact therebetween. The outer ends of the upper faces of the arms 23 serve as stops by engagement with the lower face of the body bolster 10, to limit the swinging movement of the carrier B. The opposed inner faces of the plates 19 are provided with U-shaped ribs 24 thereby defining roller trunnion receiving recesses 25 which are open at the upper sides to permit the trunnions of the roller to be inserted. The plates 19 are also provided with vertically extending strengthening ribs 125 on their inner faces.

The anti-friction roller C is provided with integral trunnions 26 rotatably supported in the recesses 25, and is adapted to roll between the upper face of the truck bolster 11 and the convex bearing face 18 of the head 12 of the supporting member A. The center of curvature of the bearing faces 27 of the ribs 24 is so spaced with reference to the axis of the cylindrical journal member that the upper surface of the roller C will be spaced slightly from the convex bearing face 18, when the retaining member is supported by the cylindrical journal member 20, thereby permitting a free swinging movement of the carrier B when the body bolster 10 is moved upwardly with reference to the truck bolster 11.

In assembling my improved side bearing, the roller C is inserted between the plates 19 of the carrier B and the trunnions 26 passed into the recesses 25 through the open upper ends thereof. It will be noted that

when the roller has thus been inserted in the carrier, the same is retained in position by the side walls 19 and the U-shaped ribs 24 thereby holding the same in position and permitting the removal thereof only in a vertical direction. The carrier B is then assembled with the supporting member A by passing either of the arms 13 or 14 of the supporting member through the space between the cylindrical journal member 20 and the roller C and seating the journal member 20 in the depression 16 of the supporting member A. The supporting member A is then fixedly secured to the body bolster 10 by means of the rivets 15, thereby holding the three parts forming the side bearing in permanently assembled relation. In this connection it is pointed out that the journal member 20 is confined between the lower face of the body bolster and the supporting member A and that the plates 19, which are formed integral therewith, prevent lateral displacement of the retaining member, thus holding the same in permanently assembled relation with the supporting member. The roller C is held in permanently assembled relation with the retaining member by engagement of the upper portion of the roller with the convex bearing face 18, whereby upward movement of the roller to an extent to permit disengagement of the trunnions from the recesses 25, is prevented. As the swinging movement of the retaining member is limited, by the ends of the arms 23 coming in contact with the lower face of the body bolster, to an extent to prevent the roller from passing beyond the ends of the convex face 18, said roller cannot be disengaged from the retaining member without removing the latter from the support A.

In the operation of my improved side bearing, as the body bolster 10 and the truck bolster 11 rotate relatively and approach each other, the anti-friction roller C will roll between the upper face of the truck bolster and the convex face 18 of the supporting member, the pressure being transmitted through the member A to the body bolster. During this operation the retaining member B swings outwardly with the roller. This rolling action will continue until the retaining member B reaches one of the extreme positions where movement is arrested by the arms 23 engaging with the body bolster 10. One of said extreme positions is shown by dotted lines in Fig. 1. Upon removal of the pressure from the side bearing member and the separation of the body bolster and truck bolster, the supporting member A will move upwardly independently of the retaining member B a slight distance, until the journal member 20 is supported by the curved bearing face 17, whereupon the retaining member will act in the manner of a pendulum and swing back to normal posi-

tion, due to the force of gravity and thereby automatically center the roller without the aid of springs or other relatively frail means.

I have herein shown and described what I now consider the preferred manner of carrying out my invention, but all changes and modifications are contemplated that come within the scope of the claims appended hereto.

I claim:

1. In a side bearing for railway cars, the combination with a supporting member having a convex lower bearing face; of a pendulum swingingly supported by said member; and an anti-friction roller carried by said pendulum and co-operable with said convex bearing face.

2. In a side bearing, the combination with a one piece supporting member having a lower bearing face; of a one piece pendulum swingingly supported by said member; and an anti-friction roller co-operable with said bearing face and having integral trunnions rotatably supported by said pendulum.

3. In a side bearing, the combination with a one piece supporting member having a depressed bearing portion in its upper face and a convex lower bearing surface; of a pendulum comprising a pair of side members connected by an integral journal member, said side members being each provided at their lower ends with bearing recesses on the inner faces thereof, said bearing recesses being open at the top and provided with guides extending upwardly from said bearing recesses and having the upper ends thereof spaced from said lower convex bearing face, said journal member being seated in said depressed bearing portion of said supporting member; an anti-friction roller having integral trunnions seated in said bearing recesses; and means for securing said supporting member to the bottom face of the upper truck bolster, whereby the journal member of said pendulum is confined between the lower face of said bolster and the supporting member, and all the parts are held in assembled relation.

4. In a side bearing, the combination with a one piece supporting member having a convex lower bearing surface; of a one piece pendulum having integral means thereon for pivotally supporting the pendulum on said supporting means, said pendulum and supporting member having co-acting means thereon for preventing separation of said pendulum and supporting member when the supporting member is secured in position on the body bolster; means for securing the support to the body bolster; and an anti-friction roller co-operable with said convex bearing face, having integral trunnions rotatably supported by said pendulum; and means on said pendulum and co-acting with

the trunnions of said anti-friction rollers for preventing separation of the anti-friction roller and the pendulum, when the parts are in assembled relation.

5 5. In a side bearing, the combination with a one piece supporting member, having a convex lower bearing surface; of a one piece pendulum having integral means thereon for pivotally supporting the pendulum on 10 said supporting means, said pendulum and supporting means having co-acting means thereon for preventing separation of said pendulum and support when the support is secured in position on the body bolster; 15 means for securing the support to the body bolster; and an anti-friction roller co-operable with said convex bearing face, having integral trunnions rotatably supported by said pendulum; means on said pendulum 20 and co-acting with the trunnions of said anti-friction rollers for preventing separation of the anti-friction roller and the pendulum, when the parts are in assembled relation; and means for limiting the swinging 25 movement of the pendulum to prevent the roller from moving out of contact with the convex bearing face.

6. In a side bearing for railway cars, the combination with a one piece supporting 30 element secured to the lower face of the body bolster, and having a bearing on the upper portion thereof and a convex bearing face on the lower portion thereof; of a one piece swinging carrier having pivotal means 35 at the upper end thereof integral therewith and confined against displacement between said supporting surface and the lower face of said body bolster; and an anti-friction roller supported by said carrier and co-acting 40 with said convex bearing surface, said carrier having means thereon for confining said roller when the parts are in assembled relation.

7. In a side bearing for railway cars, the 45 combination with a supporting member secured to the body bolster and having a lower bearing surface; of a carrier swingingly supported by said member; and a roller carried by said carrier and co-acting 50 with said bearing surface, said supporting member, carrier and roller having co-acting means thereon for preventing separation thereof when assembled and secured to the body bolster.

55 8. In a side bearing for railway cars, the combination with a one piece supporting member secured to the body bolster and having a lower bearing surface; of a one piece carrier swingingly supported by said 60 member; and a roller carried by said carrier and co-acting with said bearing surface;

said carrier and roller having co-acting means thereon, operative to prevent separation thereof when the same are assembled and said supporting member is secured in 65 position on said body bolster.

9. A three part side bearing comprising: a support secured to the body bolster, said support having a lower bearing face thereon; a carrier swinging from the support; 70 and a roller carried on the lower end of said carrier and co-acting with said lower bearing surface, all of said parts having co-acting means thereon integral therewith for preventing separation thereof when assembled. 75

10. A side bearing consisting of, a unitary support having a lower bearing face, said support being secured to the body bolster, a unitary carrier having means integral 80 therewith for pivotally connecting the same to the support, and a unitary anti-friction element co-acting with said bearing face and having means integral therewith rotatably supporting the same on lower end of said 85 carrier.

11. In a side bearing, the combination with a supporting element secured to the body bolster and having a lower bearing surface; of an anti-friction roller co-acting 90 with said bearing surface; and a carrier for swingingly supporting said anti-friction roller, said carrier being pivotally hung from said support and having means thereon at the upper end co-acting with the body 95 bolster to limit the swinging movement to prevent the roller from traveling beyond the end of said bearing surface.

12. In a side bearing for railway cars, the combination with a support secured to the 100 body bolster, said support being provided with a depression in the upper face thereof and with a lower bearing surface; of a carrier comprising a pair of side plates arranged on opposite sides of said support, 105 said side plates being connected at their upper ends by a cylindrical bearing portion, said bearing portion being seated in said depression, and the lower ends of said side plates being provided with anti-friction 110 roller supporting means; and an anti-friction roller co-acting with said lower bearing face, said roller being rotatably mounted on said roller supporting means.

In witness that I claim the foregoing I 115 have hereunto subscribed my name this 2nd day of January, 1923.

JOHN F. O'CONNOR.
